The ornamental design for a head for electric toothbrush, as shown and described.

DESCRIPTION

FIG. 1 is a perspective view of a head for electric toothbrush; FIG. 2 is a front elevation view thereof; FIG. 3 is a right-side elevation view thereof; FIG. 4 is a rear elevation view thereof; FIG. 5 is a left-side elevation view thereof; FIG. 6 is a top plan view thereof; FIG. 7 is a bottom view thereof; and, FIG. 8 is an enlarged partial perspective view thereof. Features rendered in evenly dashed lines are features of the article of manufacture that form no part of the claim. Boundary lines, represented by dot-dash lines, define the bounds of the claimed design.
